Attorney, Agent, or Firm-Price, Gess & Ubell

[57] **CLAIM**

The ornamental design for a toy robot watch, substantially as shown and described.

DESCRIPTION

FIG. 1 is a right front perspective view of a toy robot watch showing my new design;

FIG. 2 is a front elevational view thereof;

FIG. 3 is a right side elevational view thereof;

FIG. 4 is a left-side elevational view thereof;

FIG. 5 is a rear elevational view thereof;

FIG. 6 is a top plan view thereof;

FIG. 7 is a bottom plan view thereof;

FIG. 8 is a right front perspective view of the robot watch portion of the robot watch, with the holder/strap omitted for clarity of disclosure;

FIG. 9 is a front elevational view of FIG. 8;

FIG. 10 is a right side elevational view of FIG. 8;

FIG. 11 is a left side elevational view of FIG. 8;

FIG. 12 is a rear elevational view of FIG. 8;

FIG. 13 is a top plan view of FIG. 8;

FIG. 14 is a bottom plan view of FIG. 8;

FIG. 15 is a right front perspective view of FIG. 8 reconfigured as a robot with parts thereof in alternate positions;

FIG. 16 is a front elevational view of FIG. 15;

FIG. 17 is a right side elevational view of FIG. 15;

FIG. 18 is a left side elevational view of FIG. 15;

FIG. 19 is a rear elevational view of FIG. 15;

FIG. 20 is a top plan view of FIG. 15;

FIG. 21 is a bottom plan view of FIG. 15;

FIG. 22 is a top plan view of the holder/strap portion of the watch with the robot watch portion omitted for clarity of illustration;

FIG. 23 is a bottom plan view of FIG. 22.
